COLLAPSIBLE SAW HORSE LEG

Reine Chew, 3106 W. Garfield, Phoenix, Ariz. 85009

Filed Mar. 11, 1968, Ser. No. 10,907

Term of patent 14 years

U.S. Cl. D54—1
Int. Cl. D25—99; D8—99

FIGURE 1 is a perspective view of a collapsible saw horse leg, showing my new design;

FIGURE 2 is a bottom plan view thereof;

FIGURE 3 is a side elevational view thereof, with a portion of a saw horse indicated in broken line for illustrative purposes only; and

FIGURE 4 is an end elevational view thereof, as taken from the left hand side of FIGURE 3.

I claim:

The ornamental design for a collapsible saw horse leg, as shown and described.
